EYEGLASS FRAME

Alexander Kono, Woodside, N. Y., assignor to Kono Manufacturing Co., Inc., Woodside, N. Y., a corporation of New York

Application December 5, 1955, Serial No. 39,159

Term of patent 14 years

(Cl. D57—1)

Fig. 1

Fig. 1 is a perspective view of an eyeglass frame showing my new design; and

Fig. 2 is a side elevation view thereof.

The dominant feature of my design resides in the portions shown in full lines on the drawing.

I claim:

The ornamental design for an eyeglass frame, as shown and described.
